INVENTOR

Cecilia Bailie

By W. W. Williamson Atty.

UNITED STATES PATENT OFFICE.

CECILIA BAILIE, OF CAMDEN, NEW JERSEY.

BRASSIÈRE ANCHOR.

Application filed June 9, 1925. Serial No. 35,923.

My invention relates to new and useful improvements in a brassière anchor, and has for its primary object the provision of means to substantially retain the brassière in a normal position and condition under all circumstances.

Another object of my invention is to provide in a device of this character the combination with a garment having a relatively fixed position on a wearer, such as a corset or girdle, and a second garment, such as a brassière, worn over the first mentioned garment and being relatively loose and capable of displacement, of hooks connected by elastic or resilient means to the inside of the outer garment for engagement with a coacting member or pin bar attached to the outside of the undergarment or corset.

A further object of my invention is to produce an anchor for brassières which will be of unique construction and comprise two coacting members, one of which is provided with an elastic band for attachment to a garment.

With these ends in view, this invention consists in the details of the construction and combination of elements hereinafter set forth and then specifically designated by the claims.

In order that those skilled in the art to which this invention appertains, may understand how to make and use the same, I will describe its construction in detail, referring by numerals to the accompanying drawing forming a part of this application, in which:—

Fig. 1, is a perspective view of two garments on a wearer showing an application of the brassière anchor constructed according to my invention.

Fig. 2, is an enlarged perspective view of the brassière anchor per se.

Fig. 3, is an edge or plan view of the pin bar showing one pin open and the other closed.

Fig. 4, is an inner face view thereof.

In carrying out my invention as herein embodied, 10 represents an under garment, such as a corset or girdle, which is relatively fixed when being worn and over this under garment is another or outer garment 11, such as a brassière, which has a tendency to become displaced or in other words the lower edge or portion of said outer garment often "rides" up due to the movements of the wearer's body thus causing discomfiture to

the wearer and producing an untidy appearance to the clothes.

To overcome the objections or disadvantages enumerated above I provide a brassière anchor including a hook 12 attached to the inside of the outer garment or brassière 11 through the medium of an elastic band or other equivalent member 13 the latter having only the end opposite the hook secured to the garment.

The hook 12 is preferably constructed from a piece of thin metal so bent or fashioned as to provide a body 14 having a slot 15 therein for the reception of the elastic band or tape, said slot being at the upper end of the body opposite the prong 16 which is bent back upon the body and has an inwardly curved lip 17 at its free end. The curved lip lies in close proximity to the body so as to act as a closure while the terminus of said lip is spaced from the prong to provide a passage to the space within the lip.

The hook is adapted to engage the coacting member of the anchor or pin bar 18 attached to the outside of the under garment 10, such as the corset or girdle, after the outer garment or brassière 11 has been put on, which may be done by stretching the elastic tape until the lip and prong of the hook will pass beneath the cross piece 19 of the pin bar. The cross piece 19 may be formed of suitable material, such as a strip of metal, and has each end curved or bent inward to produce a pin keeper 20.

To each end of the cross piece is secured a U-shaped pin 21 by means of one of its arms leaving the other arm free for insertion in the garment after which the pointed terminal may be placed in the keeper to hold the pin bar in place and prevent injury to the wearer.

In practice any desirable number of the anchors may be employed but generally two are used in which case the pin bars are placed on the corset or girdle so as to assume a position to the rear of the hips at any suitable height and the hooks are attached to the brassière in order to engage with said pin bars.

By fastening the two garments together in this manner the outer garment will not "ride" up over the under garment, due to the movements of the wearer's body, and said outer garment will always be held in its proper position by the "pull" of the elastic

tape thus always keeping said outer garment in an unruffled condition without binding the wearer.

Because of the shape of the pin 21 the chances of tearing the garment is reduced to a minimum as the unobstructed curved portions will not pinch or cut the goods and because of the separated points of attachment of the pins on a pin bar the latter will 10 not lose its position or become twisted.

Of course I do not wish to be limited to the exact details of construction as herein shown as these may be varied within the limits of the appended claim without departing from the spirit of my invention.

Having thus fully described my invention, what I claim as new and useful is:—

As an article of manufacture, a brassière anchor comprising a hook including a body having a slot at its upper end, an integral 20 upturned prong terminating in a curved lip, the terminal edge of said lip being spaced from the inner face of said prong, a strip of elastic tape secured to the body and passing through said slot, and a pin bar including a cross piece for coaction with the hook, said cross piece having inturned curved keepers and U-shaped pins secured to the ends of said cross piece with their free arms 25 adapted for insertion in the keepers.

In testimony whereof, I have hereunto affixed my signature.

CECILIA BAILIE.
